UNITED STATES PATENT OFFICE.

JACOB WALTER, HARRY J. BUTTERWORTH, AND OSCAR J. SIGLER, OF MANSFIELD,
OHIO, ASSIGNEES OF ONE-FIFTH TO CHARLES M. ROWLAND, OF MANSFIELD, OHIO.

COMBINED VAPORIZER AND MIXER.

1,228,082.

Specification of Letters Patent.

Patented May 29, 1917.

Application filed May 10, 1916. Serial No. 96,732.

To all whom it may concern:

Be it known that we, JACOB WALTER, HARRY J. BUTTERWORTH, and OSCAR J. SIGLER, citizens of the United States of America, residing at Mansfield, in the county of Richland and State of Ohio, have invented certain new and useful Improvements in Combined Vaporizers and Mixers, of which the following is a specification.

10 This invention relates to a combined vaporizer and mixer for use in the operation of internal combustion engines.

The primary object of this invention comprises means for vaporizing liquid hydrocarbon fuels and saturating or mixing atmospheric air with the volatile constituents thereof, thereby maintaining the normal specific gravity of the charge by admitting the charge to the cylinder at atmospheric 20 temperature.

A further object of this invention is to afford facilities for vaporizing liquid hydrocarbon fuel for starting internal combustion engines and to provide means for continually thereafter vaporizing said hydrocarbon liquid fuel through the medium of the exhaust gases of the engine.

Another object of this invention is to afford means for automatically controlling the supply of liquid hydrocarbon fuel and atmospheric air for charging the cylinders with an explosive mixture, the quantity delivered to the cylinders being governed by the speed of the engine, and the means being automatically operable by the suction created by the pistons of the engine through the medium of the air valve to increase or decrease the supply of the explosive mixture as the speed of the engine varies.

40 Other objects of the invention are to combine in a self-contained device, a vaporizer, a mixer and a silencer and construct it in a simple and efficient manner to perform the objects set out with a minimum number of 45 parts.

These and other objects are attained by the mechanism illustrated in the accompanying drawings in which:

Figure 1 is a side elevation of a conventional form of motor showing the invention connected to the intake and exhaust manifolds.

Fig. 2 is a vertical central section of the invention showing the main supply needle valves and air valve closed.

Fig. 3 is a sectional detail view of one of the supply valves showing the inclined bores, valves and valve mechanism.

Fig. 4, a side elevation of the invention showing a supply pipe connected to the valves and means of operating the auxiliary valve and closing the circuit of the electrical heater that vaporizes the fuel preparatory to starting the engine.

Fig. 5 is a cross sectional view of the invention taken on the line BB of Fig. 4 showing the electrical heater and vertically 65 sectional view of the auxiliary supply valve.

Fig. 6 is a bottom plan view of the air valve on the line AA of Fig. 4.

Fig. 7 is a plan view of Fig. 2, partly in section showing a series of perforations provided in a pre-determined portion of a drum.

Fig. 8 is a cross sectional view of Fig. 2 75 taken on the line CC of Fig. 2, the connection between the lever link bars and the valve link being omitted for the sake of clearness.

Similar reference characters refer to similar parts throughout the several views.

In the drawings, reference numeral 1 represents a conventional type of an internal combustion motor, 2 the intake manifold, 3 the exhaust manifold and 4 the engine feed 85 pipe.

The preferable specific means employed in constructing the combined vaporizer and mixer is as follows:

A vaporizer 5, preferably made tubular 90 in form is provided, having both ends exteriorly threaded, and a predetermined portion of the vaporizer 5 is cut away leaving an opening at the top, which opening is covered and securely closed by a depending 95 copper plate 6, having a concave upper surface, (see Fig. 5). The plate is secured to the vaporizer by any well known fastening means.

A cylinder head 7, is mounted upon the 100 vaporizer and adjustably positioned thereon by the nut 8. The cylinder head 7 is provided with an annular groove 9, which is located in spaced and concentric relation

to the vaporizer. The head 7 is also provided adjacent to its periphery with an annular shoulder 11 to engage one end of a cylinder 12. A cylinder head 13 is mounted 5 upon the vaporizer in spaced relation from the head 7, and it is also provided with an annular groove and a shoulder coincident with the shoulder and groove formed on the head 7.

- 10 In assembling the parts, the cylinder head 7 is first mounted upon the vaporizer, one end of a drum 14 is inserted in the annular groove, one end of the cylinder is fitted to the annular shoulder 11, the opposite end thereof and the opposite end of the drum is fitted to the coincident groove and shoulder formed in the cylinder head 13. The nut 15 is then tightened forcing the cylinder heads to clamp the cylinder and drum therebetween providing a chamber 10, which surrounds the vaporizer and a chamber 16, which surrounds the drum.

15 The drum 14 is formed in its upper portion with perforations 62 through which the vaporized liquid hydro-carbon fuel is permitted to pass, as will be hereinafter noted; the said drum being also formed in its lower portion with openings 14' to permit escape of liquid fuel in the event of such 20 accumulating in the lower portion of the drum.

25 It will be observed that the arrangements above described provide concentric chambers in spaced relation to the vaporizer.

30 The cylinder 12 is connected to the feed pipe 4 of the engine by a centrally arranged upstanding flanged tubular member 17, which communicates with the chamber 16. A tubular member 18, which forms a chamber 35 for the air valve is provided upon the cylinder at one end, and it is in communication with the chamber 16. The tubular member 18 is positioned to depend from one 40 end of the cylinder, depending in a direction opposed to the upstanding flanged tubular member 17. The exhaust manifold 3 is connected to one end of the vaporizer by a connecting pipe 19 and coupling 20.

45 To provide means of deadening or muffling the sound or noise of the exhaust gases, a series of inclined baffle plates 21 are fitted in spaced relation to the inner periphery of the vaporizer so as to leave clearance spaces 22 and 23.

50 In supplying liquid hydrocarbon fuel to the vaporizer, one or more main supply valves can be used as desired. In the preferred construction as shown in the drawing two main supply valves are used, which are 55 applied to the vaporizer and constructed as follows:

60 The cylinder and drum are provided with alined apertures to receive the valve casings 24 and 25 and they are secured therein, with one end projecting into the chamber 10.

The automatic fuel supply valves are constructed and operated as follows: The casting is provided with a bore *a* and a valve *b* is inserted therein, having a valve stem *c*. A disk *d* is secured or formed thereon to fit 70 the bore *a*. The valve stem carries another disk *e* that fits the bore and provides a rest for the coil spring *f*, which normally maintains the valve upon its seat. An aperture *g* is formed in the valve casing intersecting 75 with an aperture *h* that communicates with a valve opening *i*. A series of inclined bores *j* are formed around the valve in cone shape, one end of the bores communicating with the bore *a* and the other ends radiating and 80 opening into the chamber 10, which has the effect of radially spraying the fuel upon the vaporizer. The valve stems are slidably fitted in apertures formed in plugs 33 and 34, thereby maintaining the stem in alignment at all times in conjunction with the 85 disks hereinbefore described.

80 The needle valves are guided and maintained in alignment with their respective seats by the disk members *d* and *e*, which 90 are secured to the valve stem. The open ends of the casings are closed by the screw threaded plugs 33 and 34. The cylinder head 7 is provided with an inwardly extending ear 35 and lever link bars 36 are 95 pivotally attached thereto.

95 The lever link bars extend rearwardly from their pivoted connection passing through slots provided in the main valve casings, and their free ends are pivotally 100 attached to a link 37, preferably in the form of a ring which spans the drum. The link is also secured to a stem 38 of an air valve 39, which is normally maintained closed or 105 in contact with its seat 40 by a coil spring 41, which is interposed between the washer 42 and the spider 43 provided on the tubular member 18. The main supply valves 29 and 30 are connected to the lever link bars 36 by the pins 44 and 45 and a slot 46 is 110 formed in the stem of the valve 30 to permit the valve 29 to be fully opened before movement is imparted to the valve 30 by the lever link bar.

115 The essential elements of the vaporizer, arrangements and combinations thereof, hereinbefore described are common to the use and construction of the vaporizer and mixer when the engine is being operated after starting, but does not include the 120 means of starting the engine which will now be described.

An electric heater 47 is mounted upon the plate 6 and connected to a battery by the wires 48, the circuit, however, is normally 125 interrupted and the current is not conducted to the heater except under certain conditions which will be described hereafter. An auxiliary valve casing 49 is fitted to alined apertures formed in the cylinder and drum so as 130

to leave one end projecting above the cylinder and the other end projecting into the chamber 10. The end of the valve casing is closed or plugged and an opening 50 formed 5 therein having a valve seat formed on its open end.

An auxiliary needle valve 51 having a stem smaller in diameter than the inner periphery of the valve casing normally maintains the valve in closed position and it is held in alinement with the valve seat during its reciprocation by a cap 53, having an aperture to receive the valve stem, and having threaded connection with the casing 49. 10 The auxiliary valve casing 49 is formed at an appropriate point with an aperture 52 to establish communication between the interior of the casing and the supply pipe 60, the needle valve 51 being reduced in diameter coincident with such openings to insure the proper admission of the fuel at this point. 15

A bracket 54 is secured to the top of the cylinder and a bell crank 55 is pivotally secured thereto. The bell crank is pivotally connected to the bifurcated end of the valve stem and to one end of a connecting rod 56, and the opposite end of the link connecting bar is mounted for reciprocation at any convenient point. A bracket 57 is secured to the top of the cylinder and located in close proximity to the valve casing 49.

A contact 58 having a downwardly projecting end is secured to the bracket in alinement with a spaced apart yielding contact 59, and both contacts extend over the top of the valve stem. When movement is imparted to the valve stem to open the valve, the top of the valve stem contacts with the 20 yielding contact 59 and forces it to contact with the contact 58 closing the circuit to the heater 47 and heating the heater for the purpose of vaporizing the liquid hydrocarbon fuel as it is permitted to flow through the 25 jet 50 of the auxiliary valve. Reference numeral 60 indicates a supply pipe that is connected to the main supply valve casings and the auxiliary valve casing, and reference numeral 61 indicates a butterfly throttle 30 valve of the ordinary type.

The above describes the preferable specific construction and arrangement of the parts used in carrying out the principles of the invention. It will be apparent, however, to those skilled in the art, that changes and alterations can be made in the specific means described without departing from the spirit of the present invention.

The operation of vaporizing the liquid hydrocarbon fuel and mixing and saturating it with air at atmospheric temperature will now be described.

Kerosene oil or any other kind or variety of liquid hydrocarbon fuel is conducted by 65 gravity or otherwise from any convenient

source of supply through the supply pipe 60 which is in communication with the chambers of the main supply valve casings 24 and 25, and the chamber of the auxiliary valve casing 49 to maintain the chambers of the 70 above described casings filled with the liquid hydrocarbon fuel.

When it is desired to start the engine or motor, the operator pulls the connecting rod 56, imparting movement to the bell crank 55, 75 which in turn raises the valve stem of the auxiliary valve until it contacts with the yielding contact 59 and forces it in contact with the contact 58 closing the circuit and conducting the current to the heater to heat 80 same for vaporizing purposes, simultaneous with the raising of the valve stem of the auxiliary valve for the purpose of closing the circuit to the heater, the auxiliary valve 51 is opened permitting the liquid hydrocarbon fuel to pass out through the valve openings in the supply valve casings and drop or flow upon the heater 47, which vaporizes the liquid hydrocarbon, the volatile constituents thereof, passing out through 85 the perforations 62 formed in the drum 14 into the cold air chamber 16, where it mixes with and saturates the air to form an explosive mixture at atmospheric temperature prior to being conducted through the feed 90 pipe 4 and intake manifold 2 to the cylinders of the motor by the suction created by the pistons.

Attention is called to the fact that when the motor is turned over preparatory to 100 starting that the suction created by the pistons raises the air valve 39 and permits the air to be drawn by the suction of the pistons into the chamber of the tubular member 18, thence into the chamber 16, which communicates therewith and surrounds the drum 14. As the liquid hydrocarbon fuel is being 105 vaporized by the heater 47, the volatile constituents thereof rise and pass out through the perforations 62 into the chamber 16.

The volume of the volatile constituents of the liquid hydrocarbon fuel, as it is being vaporized, is forced to pass through the perforations 62 formed in the drum 14 to break up or atomize it to further assist in mixing 110 the vapors with the atmospheric air.

It is apparent, however, that the explosive mixture can be formed without forcing the volatile constituents of the liquid hydrocarbon fuel to pass through a series of perforations.

The above describes the method and means of starting the motor, the operation of the motor after it is started will now be described.

When the motor is started, the auxiliary valve 51 is permitted to seat, thereby cutting off the supply of liquid hydrocarbon fuel that flows or drops through the valve opening 50 when the valve is open, and at the 130

same time the connection between contacts 58 and 59 is broken or interrupted breaking the circuit, thereby preventing the current from heating the heater 47. After the motor 5 starts, the exhaust gases from the motor are discharged into the chamber A of the vaporizer 5, thereby constantly maintaining the plate 6 in a heated state.

The suction created by the pistons of the motor automatically raises the air valve 39 from its seat permitting air at atmospheric temperature to be drawn into the chamber 16 and around the drum 14, and simultaneously with the raising of the air valve from 15 its seat the main supply valves 29 and 30 are opened permitting the liquid hydrocarbon fuel to flow into the valve openings and out through the inclined bores *j*, spraying the liquid hydrocarbon fuel upon the vaporizing plate 6.

As the speed of the engine varies, the air valve is opened more or less by the suction of the pistons of the motor which simultaneously operates the mechanism connected to 25 the main supply valves allowing a sufficient amount of liquid hydrocarbon fuel to pass through the main supply valves, and to be sprayed upon the vaporizing plate to equalize and feed fuel in proper proportion to the 30 air admitted through the air valve, thereby providing means of automatically governing the amount of hydrocarbon fuel and air admitted to the cylinders at atmospheric temperature to form or provide a proper 35 explosive mixture. The exhaust gases are baffled and the sound muffled or silenced by the baffle plates 21, which are arranged within the interior of the vaporizer so as to leave clearance spaces for the escape of the 40 exhaust gases into the atmosphere.

Attention is called to the fact that the proper mixture of the vaporized volatile constituents of the liquid hydrocarbon fuel and air at atmospheric temperature is constantly and automatically maintained thereby providing a proper explosive mixture by the suction created by the pistons operating upon the air valve 39. When the speed increases a richer charge is drawn into the 50 cylinder and when the speed decreases, a thinner mixture is drawn into the cylinder, thereby automatically regulating the supply of the explosive mixture for charging the cylinders according to the speed of the 55 motor or power required. This richness of the mixture is obvious from the fact that the valve 39, which is controlled solely by the suction of the cylinders, will, under comparatively light suction, as when the engine 60 is operated at low speed influence but one of the fuel inlet valves, while under greater suction the additional inlet valve will be operated to increase the fuel supply. Therefore the position of the valve 39, which position is controlled by the speed of the engine 65

or the power required, governs the inlet valve, thus, in effect, increasing the fuel supply in direct proportion to the suction.

The device herein described and claimed is constructed primarily for vaporizing and 70 mixing kerosene oil for use in the operation of internal combustion engines, but it is apparent that it will operate with equal facility in burning any kind or variety of liquid hydrocarbon fuel such as gasolenes, 75 crude oil, distillate, and alcohol.

We claim:

1. In a combined vaporizer and mixer for internal combustion engines, a vaporizer, a drum having imperforate side walls and 80 provided at the top with perforations which permit the escape of the volatile constituents of the vaporized hydrocarbon to mix with air at atmospheric temperature, a cylinder surrounding said drum, means to conduct 85 liquid hydrocarbon fuel to the vaporizer, means for heating the vaporizer by the exhaust gases of the engine, and means operated by the suction of the engine to mix air at atmospheric temperature with the volatile constituents of the liquid hydrocarbon fuel.

2. In a combined vaporizer and mixer for internal combustion engines, a vaporizer, a drum having imperforate side walls and 95 provided at the top with perforations which permit the escape of the volatile constituents of the vaporized hydrocarbon to mix with air at atmospheric temperature, a cylinder surrounding said drum, means to conduct liquid hydrocarbon fuel to the vaporizer, means for heating the vaporizer by the exhaust gases of the motor, means to mix air at atmospheric temperature with the volatile constituents of liquid hydrocarbon fuel, and 100 auxiliary means for vaporizing hydrocarbon fuel preparatory to starting the motor.

3. In a combined vaporizer and mixer for internal combustion motors, a vaporizer having a portion cut away, a plate secured 110 to the vaporizer to close said opening, a drum provided with a plurality of perforations spaced apart from the vaporizer and arranged in concentric relation thereto to form a chamber, a cylinder arranged to surround said vaporizer to form a chamber, means to conduct liquid hydrocarbon to the vaporizer and means operable by the suction of the pistons of the motor to supply atmospheric air to one of the chambers to 115 mix with the volatile constituents of the vaporized liquid hydrocarbon fuel flowing from the other chamber.

4. In a combined vaporizer and mixer for internal combustion motors, a tubular vaporizer, cylinder heads mounted upon the vaporizer, a cylinder and a drum held and maintained by said heads in concentric relation to the vaporizer to provide chambers, a heater mounted upon the vaporizer, means 120

to close and interrupt the circuit that conducts an electrical current to said heater to heat same; said means also operating an auxiliary valve to permit the flow of the liquid hydrocarbon fuel to the vaporizer, and means to utilize the exhaust gases of the engine to heat the vaporizer.

5. In a combined vaporizer and mixer for internal combustion motors, a tubular vaporizer, cylinder heads mounted upon the vaporizer, a cylinder and a drum held and maintained by said head in concentric relation to the vaporizer to provide chambers, a heater mounted upon the vaporizer, means to close and interrupt the circuit that conducts an electrical current to said heater to heat same; said means also operating an auxiliary valve to permit the flow of the liquid hydrocarbon fuel to the heater, means to conduct the flow of liquid hydrocarbon fuel to the vaporizer, means to utilize the exhaust gases of the engine to heat the vaporizer, and means to baffle the exhaust gases in their vaporizing area.

25 6. In a device for vaporizing and mixing liquid hydrocarbon fuel for use in internal combustion engines, a vaporizer heated by exhaust gases, cylinder heads mounted upon said vaporizer, a cylinder and a drum clamped and maintained in concentric relation to said vaporizer by said cylinder heads to provide chambers, means automatically operable by the suction of the engine to admit atmospheric air to one of the chambers and to conduct liquid hydrocarbon fuel to the vaporizer, whereby the air at atmospheric temperature is caused to mix with the liquid hydrocarbon fuel after vaporization to form an explosive mixture.

10 7. In a device for vaporizing and mixing liquid hydrocarbon fuel for use in internal combustion engines, a vaporizer heated by exhaust gases, cylinder heads mounted upon said vaporizer, a cylinder and a drum clamped and maintained in concentric relation to said vaporizer by said cylinder heads to provide chambers, means automatically operable by the suction of the engine to admit atmospheric air to one of the chambers and to conduct liquid hydrocarbon fuel to the vaporizer, whereby the air at atmospheric temperature is caused to mix with the volatile constituents of the liquid hydrocarbon fuel to form an explosive mixture, and an electric heater arranged within the drum and adjacent the vaporizer for the initial vaporization of the liquid hydrocarbon.

8. In a device for vaporizing liquid hydrocarbon fuel and mixing it with atmospheric air, a vaporizer adapted to be heated by the exhaust gases of the engine, means of maintaining a cylinder and a drum in concentric relation to the vaporizer to provide chambers, means to automatically sup-

ply liquid hydrocarbon fuel to the vaporizer within the drum and to admit air at atmospheric temperature to the cylinder beyond the drum to mix with the volatile constituents of the liquid fuel, said means being operable by the suction of the engine.

9. In a device for vaporizing liquid hydrocarbon fuel and mixing it with atmospheric air, a vaporizer adapted to be heated by the exhaust gases of the engine, means of maintaining a cylinder and a drum in concentric relation to the vaporizer to provide chambers, means to automatically supply liquid hydrocarbon fuel to the vaporizer and to admit air at atmospheric temperature to mix with the volatile constituents of the liquid fuel, said means being operable by the suction of the engine, an electric heater mounted upon the vaporizer, and an auxiliary means adapted to conduct a supply of liquid hydrocarbon fuel to the heater to provide a charge of explosive mixture for starting purposes.

10. In a combined vaporizer and mixer for internal combustion engines, a vaporizer adapted to be heated by exhaust gases, means for providing chambers around said vaporizer, means for conducting liquid hydrocarbon to the interior of one of said chambers and spraying it upon the vaporizer, and means to draw air at atmospheric temperature into the other chamber for mixing with the volatile constituents of the vaporized fuel; both of the last mentioned means being automatically operated by the suction of the motor.

11. In a combined vaporizer and mixer for internal combustion engines, a vaporizer adapted to be heated by exhaust gases, means for conducting liquid hydrocarbon to the interior of one of said chambers and spraying it upon the vaporizer, and means to draw air at atmospheric temperature into the other chamber for mixing with the volatile constituents of the vaporized fuel; both of the last mentioned means being automatically operated by the suction of the motor, and means in the vaporizer for interrupting the direct current of the exhaust gases to increase the vaporizing effect thereof.

12. In a combined vaporizer and mixer for internal combustion engines, a vaporizer adapted to be heated by exhaust gases, means for conducting liquid hydrocarbon to the interior of one of said chambers and spraying it upon the vaporizer, means to draw air at atmospheric temperature into the other chamber for mixing with the volatile constituents of the vaporized fuel; both of the last mentioned means being automatically operated by the suction of the motor, means in the vaporizer for silencing the noises of the exhaust gases, an electric heater mounted on the vaporizer normally inoperative to produce heat, means for conducting

hydrocarbon liquid fuel to the heater and means adapted to close the circuit to the heater and simultaneously therewith operate the means that permits the flow of liquid hydrocarbon fuel to the heater.

13. A device of the character described for internal combustion engines, a vaporizer heated by exhaust gases, means for providing chambers around said vaporizer, means 10 of conducting hydrocarbon to the interior of one of said chambers and to the vaporizer and means of supplying air at atmospheric temperature to the other chamber, both of said last mentioned means being simultaneously and automatically operated by the suction of the engine.

14. A device of the character described for internal combustion engines, a vaporizer heated by exhaust gases, means for providing 20 chambers around said vaporizer, means of conducting hydrocarbon to the interior of one of said chambers and to the vaporizer, means of supplying air at atmospheric temperature to the other chamber, both of said last mentioned means being simultaneously and automatically operated by the suction of the engine, a heater mounted on the vaporizer and means of conducting hydrocarbon fuel thereto operable by hand manipulation.

30 15. A device of the character described for internal combustion engines, a vaporizer heated by exhaust gases, means for providing chambers around said vaporizer, means

for conducting hydrocarbon to the interior 35 of one of said chambers and to the vaporizer, means for supplying air at atmospheric temperature to the other chamber, both of said last mentioned means being simultaneously and automatically operated by the suction 40 of the engine, a heater mounted on the vaporizer, means of conducting hydrocarbon fuel thereto operable by hand manipulation, and means provided in the interior of the vaporizer to muffle the sound of the exhaust 45 gases and interrupt the direct flow of the exhaust gases to increase the vaporizing effect.

16. In a combined vaporizer and mixer for internal combustion engines, a vaporizer, 50 a drum having imperforate side walls and provided with a top with perforations which permit the escape of the volatile constituents of the vaporized hydrocarbon to mix with air at atmospheric temperature, a cylinder 55 surrounding said drum, means to conduct liquid hydrocarbon fuel to the vaporizer, means for heating the vaporizer, means to mix air at atmospheric temperature with the volatile constituents of liquid hydrocarbon 60 fuel, and auxiliary means for vaporizing hydrocarbon fuel preparatory to starting the motor.

In testimony whereof we affix our signatures.

JACOB WALTER.
HARRY J. BUTTERWORTH.
OSCAR J. SIGLER.
